CLAIM

The ornamental design for a roll of pre-cut strips of tape, as shown and described.

DESCRIPTION

FIG. 1 is a perspective view of a design for a roll of pre-cut strips of tape, with the roll at least partially unrolled; FIG. 2 is a front view of the roll of pre-cut strips of tape shown in FIG. 1;

FIG. 3 is a first side view of the roll of pre-cut strips of tape shown in FIG. 1;

FIG. 4 is a rear view of the roll of pre-cut strips of tape shown FIG. 1;

FIG. 5 is a second side view of the roll of pre-cut strips of tape shown in FIG. 1;

FIG. 6 is a top view of the roll of pre-cut strips of tape shown FIG. 1; and,

FIG. 7 is a bottom view of the roll of pre-cut strips of tape shown in FIG. 1.
